CLAIM

The ornamental design for a cart handle, as shown and described.

DESCRIPTION

FIG. 1 is a front right perspective view of the cart handle; FIG. 2 is a rear perspective view of the cart handle of FIG. 1;

FIG. 3 is a front elevation view of the cart handle of FIG. 1;

FIG. 4 is a rear elevation view of the cart handle of FIG. 1;

FIG. 5 is a top plan view of the cart handle of FIG. 1;

FIG. 6 is a bottom plan view of the cart handle of FIG. 1;

FIG. 7 is a right side view of the cart handle of FIG. 1; and,

FIG. 8 is a left side view of the cart handle of FIG. 1.

The broken line showing of the face, handle ends and back is included for the purpose of illustrating only and forms no part of the claimed design.
